REMOTE CONTROL COMBINATION LOCK

Joseph C. Allman, Joliet, Ill.

Application January 3, 1934, Serial No. 705,093

6 Claims. (Cl. 70—63)

This invention relates to a remote control magnetic lock for use in locking and unlocking doors and other closures, and which may be used advantageously for locking and unlocking doors of safes and vaults.

One of the objects of the invention is the provision of a lock of the indicated character which eliminates exterior means for locking and unlocking doors and closures, to prevent unauthorized entry and damage in attempts at burglary, or, in other words, to provide a lock which cannot be seen, felt, or picked from the exterior of the door or closure in conjunction with which it is used.

Other advantages of the invention are as follows: Mechanical contact from the outside of the door to the interiorly arranged locking mechanism is impossible. It eliminates the need of a numbered combination dial and handle, often the means of entry by clever burglary. The locking mechanism can be controlled from any convenient place located anywhere in a room or other compartment. The lock can be employed in conjunction with the doors of safes and vaults already constructed and in use. There will be no hole or aperture necessary in the door or closure which could be used to provide introduction of explosives in attempts at burglary. Expensive repairs following burglary are eliminated. The lock cannot in any manner be tampered with and, therefore, it will not be necessary to make tactical experiments inasmuch as the mechanism will be concealed from view and an opening could not be effected unless the whole structure were wrecked.

With the foregoing and other objects in view, the invention resides in the features hereinabove described and claimed and as illustrated, by way of example, in the accompanying drawings, in which

Figure 1 is an inside view of a safe door with a lock embodying features of the present invention applied thereto, its parts being shown in a relation to lock the door, and a portion of the door-supporting arm being broken away;

Fig. 2 is a section taken on the line 2—2 of Fig. 3;

Fig. 3 is a sectional view taken on the line 3—3 of Fig. 1;

Fig. 4 is an enlarged section and part elevation showing certain features of the invention;

Fig. 5 is a section through the group of tumblers.

Fig. 6 is a view on the line 6—6 of Fig. 5.

In the drawings, by way of example, the lock is shown employed in conjunction with a door 10 of a safe, a portion of which is designated 11.

The door 10 and its jamb 12 are rabbeted in a

complementary manner so that the door will be kept from moving inwardly from its closed position in contact with the jamb 12, and so that the door may be swung outwardly with respect to the jamb 12 into its opened position. In order to mount the door 10 to move in the manner stated, use is made of a supporting arm 13, which has one end pivotally connected with the jamb 12 at the inside, as at 14, and the opposite end of the arm is pivotally connected, as at 15, with the door 10 at the inside thereof. The door 10 is shown swung into its opened position in dot-and-dash lines, Fig. 1. The door 10 is of hollow construction to provide a recess 16 opening through the inside of the door 10. The door 10 in the present instance is circular.

The lock is carried by the door 10 and is arranged in the recess 16. In the illustrated embodiment, the lock includes locking bolts 17. Each bolt 17 is arranged so that its outer end may be disposed in an opening 18 in the door and an opening or recess 19 in the jamb 12 which registers with the opening 18 when the door 10 is in its closed position. The inner end of each of the bolts 17 is pivotally connected, as at 20, with a lever 21, whose fulcrum 22 is disposed horizontally and is supported by a base plate 23 secured in any practical manner to the door 10, as by the use of fastening elements 24.

Bolt projecting and retracting means is employed consisting of a rack 25 having one end pivotally connected, as at 26, with a rocker arm 27 and a link 28. The rocker arm 27 is mounted for rocking movement on a pivot 29 carried by the plate 23. The link 28 is pivotally connected with the lever 21, as at 30. The rack 25 is adapted to mesh with a gear 31 freely rotatable on an arbor or spindle 32 carried by the plate 23.

The rack 25 is under the control of permutation means consisting of a group of tumblers arranged coaxially on the spindle 32. It is to be understood that any suitable number of tumblers may be used, and in the present instance four of such tumblers are employed, the same being designated 33, 34, 35 and 36. Each of the tumblers is in the form of a disk and has a marginal notch or recess 37. The tumblers are held in spaced relation by friction spacers or washers 38 held against turning movement on the spindle 32, while the tumblers may rotate subject to the frictional resistance of the washers 38. Friction means 39 carried by the spindle 32 and acting on each tumbler, may also be employed to prevent unintentional movement or overrunning of the tumbler. The tumblers carry an arrangement

of laterally extending pins 40, and the gear 31 also has pins 41. The pins 40 and 41 cooperate with each other in the movement of the tumblers to bring about the registry of the notches or recesses 37 in the tumblers to effect the projection and withdrawal of the locking bolts 17 in a manner to be explained. It is to be understood that any preferred form of permutation means may be employed which may be changed to vary the 10 operation.

Remote control mechanism is employed to operate the tumblers 33, 34, 35 and 36. This mechanism includes a ratchet gear 42 secured to or formed integral with the gear 31 in coaxial relation and freely rotatable therewith on the spindle 32. The ratchet gear 42 is rotated in a counterclockwise direction by a pawl 43 pivotally connected, as at 44, with an arm 45 mounted for pivotal or swinging movement on the spindle 32. An electromagnet 46 carried by the base plate 23, is employed to operate the pawl 43 as connected with its arm 45, and this is accomplished by connecting the armature 47 of the electromagnet 46 with the pawl 43 by a link 48 whose opposite ends are pivotally connected, respectively, with the pawl 43 and armature 47, as at 49 and 50, respectively. The ratchet gear 42 is rotated in a clockwise direction by means similar to that used for rotating the ratchet gear 42 in a counterclockwise direction, and the means employed for rotating the ratchet gear 42 in a clockwise direction are designated 53 to 60, inclusive, to correspond to the means 43 to 50, inclusive. A coil contractile spring 61 has the opposite ends thereof connected, respectively, with the lower ends of the arms 45 and 55, to draw them toward each other. The spring 61 further serves to draw the armatures 47 and 57 out of their cores when the electromagnets 46 and 56 are deenergized, and also to normally retain the pawls 43 and 53 out of engagement with the teeth of the ratchet gear 42. Current may be supplied to the coils of the electromagnets 46 and 56 from any suitable source. The coil of the electromagnet 46 and the electromagnet 56 is connected in series with the current feed conductors 62 and 63, by wires 64 and 65 interrupted by spring contacts 66 carried by and insulated from the jamb 12 and post contacts 67 carried by and insulated from the door 10. When the door 10 is in its closed position, the contacts 67 will be in engagement with the contacts 56. The circuit leading to the coil of the electromagnet 46 is controlled by a push button 68 in the wire 64, and a similar push button designated 69 is connected with the other wire 64 forming a part of the circuit including the coil of the electromagnet 46. The push buttons 68 and 69 may be of different shapes in order to be readily distinguishable. These push buttons 68 and 69 may be located in an office, room, or compartment remote from the lock, for the purpose of operating the same to lock and unlock the door.

In order to allow the rack 25 to move down by gravity into meshing engagement with the gear 31 when the recesses or notches 37 of the tumblers are in mutual registry, there is provided a dog 70 which has pivotal movement on a horizontal pivot 71 carried by the rack 25 intermediate the ends of the dog 70. This dog has a nose 72 receivable in the notches or recesses 37 when in registry, and also has a tail 73 under the influence of a spring 74 secured to the rack, as at 75. The spring 74 constantly acts on the tail 73 to urge the nose 72 down into the notches or recesses 37 when in registry, and said spring 74

allows the dog to move on its pivot for the disengagement of the nose 72 from the notches or recesses 37. A stop pin 76 carried by the rack 25 limits the downward movement of the nose end of the dog 70. When the notches or recesses 37 are in registration, the nose 72 of the dog 70 will drop thereinto and as a consequence the rack 25 will mesh with the gear 31. The counterclockwise rotation of the gear 31 will cause the rack 25 to move to the left, and through the intervention of the link 28 and the lever 21, the bolts 17 will be retracted to unlock the door. The movement of the rack 25 to the left while the nose of the dog 70 is in the recesses, will cause the tumblers to rotate in a counterclockwise direction, during which the nose 72 will move out or leave the recesses 37 while the rack 25 will be held in mesh with the gear 31 by a pin 77 carried by the plate 23, the pin 77 engaging the edge 78 of the rack 25 for this purpose. Upon subsequent clockwise movement of the gear 31, the rack 25 will move tangentially to the right, causing the projection of the bolts 17 through the intervention of the link 28 and the lever 21. During this clockwise rotation of the gear 31, the nose of the dog resting on the tumblers, which will be transposed to take the recesses 37 out of registry, will elevate the rack 25 out of engagement with the gear 31. The pin 77 will enter a notch 79 in the rack 25, thereby locking the bolts 17 in their projected positions.

In accordance with another feature of the invention, the pin 77 carries a flat spring 80, which bears on the ratchet gear 42 to check the movement of the rack.

The ratchet gear 42 has means in the form of a radial pin 81, which cooperates with the pawls 43 and 53 to limit the rotation of the ratchet gear 42 and the gear 31 in opposite directions. When the pin 81 encounters the pawl 53, as shown in Fig. 2, the recesses 37 of the tumblers will be at their starting points.

Assuming that the parts of the lock have been put into such relationship that the bolts 17 are in their retracted positions and that the nose 72 of the dog 70 is elevated in contact with the peripheries of the tumblers, with the rack 25 in engagement with the gear 31, the lock may be operated by performing the following operations after the door 10 has been moved into its closed position to bring the contacts 67 in engagement with the contacts 56:

Turn on the electric current. Then press the button 69 a predetermined number of times to thereby repeatedly energize the electromagnet 56, causing the arm 55 to oscillate and the pawl 53 carried thereby to engage the teeth of the ratchet gear 42 to move the latter step by step a definite angular degree in a clockwise direction. This will cause the rack 25 to move tangentially to the right and through the intervention of the link 28 and the lever 21, cause the bolt 17 to be projected into the recesses 19 in the jamb 12. In effecting this result, the tumblers will not be disturbed and will remain in their starting positions. In this manner the door is locked.

Then press the button 68 a predetermined number of times to energize and de-energize the electromagnet 46 repeatedly, causing the ratchet wheel 42 to move a predetermined degree through the intervention of the arm 45 and its pawl 43. This will cause the gear 31 to rotate counterclockwise and cause one of the pins 41 carried thereby to cooperate with one of the pins 40 of the tumbler 33. The button 69 is then manipulated a predetermined number 75

of times to cause the ratchet gear 43 and the gear 31 to rotate clockwise in an obvious manner by the pawl 53, thereby causing one of the pins on the tumbler 33 to act on one of the pins on the tumbler 34. In this manner, by alternately manipulating the buttons 68 and 69 each a predetermined number of times, the tumblers may be rotated progressively until all of them move in unison to bring the recesses 37 in registry, to allow the nose 72 of the dog 70 to be projected into the recesses 37, so registered, by the spring 74, and incidentally allow the rack 25 to mesh with the gear 31. The button 68 may then be manipulated a predetermined number of times, causing the ratchet gear 42 and gear 31 to rotate in a counterclockwise direction, as indicated by the arrow in Fig. 4, thereby causing the rack 25 to move tangentially to the left, and through the intervention of the link 28 and lever 21, causing the retraction of the bolts 17. In this manner, the door 10 will be unlocked. To again lock the door, it will be necessary to manipulate the button 68 which will cause the rack 25 to move tangentially to the right by the means and in the manner described hereinbefore.

If desired, the parts of the lock may be enclosed by a casing 82, which is slotted, as at 83, to accommodate the bolt 17. The casing 82 is secured, as at 84, to the plate 23.

30 I claim:

1. In a lock, a locking bolt mounted to be projected into a locking position and also to be retracted from said position, an assembly of tumblers each having a marginal recess, said tumblers being movable to bring their recesses in registry with each other, a gear rotated by said assembly, a rack movable into and out of mesh with said gear, a movable dog carried by said rack, said dog being engageable in said recesses by resilient means when the recesses are in registry, to allow said rack to mesh with said gear, and means connecting said rack and bolt to project and retract the bolt in response to the rotation of said assembly after the dog is engaged as aforesaid.

2. In a lock, a locking bolt mounted to be projected into a locking position and also to be retracted from said position, an assembly of tumblers each having a marginal recess, said tumblers being movable to bring their recesses in registry with each other, a gear rotated by said assembly, a rack movable into and out of mesh with said gear, a movable dog carried by said rack, said dog being engageable in said recesses by resilient means when the recesses are in registry, to allow said rack to mesh with said gear, means connecting said rack and bolt to project and retract the bolt in response to the rotation of said

assembly after the dog is engaged as aforesaid, said assembly causing the dog to be disengaged from the registered recesses in response to rotation of said assembly in the bolt retracting operation, and means to retain the rack in mesh with said gear until it is demeshed by the dog being elevated by its engagement with the peripheries of said tumblers in the rotation of the latter as aforesaid, said last means engaging in a notch in the rack when the latter is in bolt projected position, to prevent retraction of the bolt, subject to the reentry of the dog in the registered recesses.

3. In a lock, a locking bolt mounted to be projected into a locking position and also to be retracted from said position, an assembly of tumblers each having a marginal recess, said tumblers being movable to bring their recesses in registry with each other, a gear rotated by said assembly, a rocker, a rack pivotally connected with said rocker so as to be movable into and out of mesh with said gear, a movable dog carried by said rack, said dog being engageable in said recesses by resilient means when the recesses are in registry, to allow said rack to mesh with said gear, and means connecting said rack and bolt to project and retract the bolt in response to the rotation of said assembly after the dog is engaged as aforesaid.

4. In a lock, a lever, locking bolts connected with said lever to be operated thereby, a rocker arm, a link whose opposite ends are pivotally connected respectively with said lever and rocker arm, a member having one end pivotally connected with the pivotal connection of said lever and rocker arm, and means to operate said member to operate said bolts through the intervention of said link and lever.

5. In a lock, a lever, locking bolts connected with said lever to be operated thereby, a link having one end pivotally connected with said lever, a member having one end pivotally connected with the remaining end of said link, and means to operate said member to operate said bolts through the intervention of said link and lever.

6. In a lock, a lever, locking bolts connected with said lever to be operated thereby, a link having one end pivotally connected with said lever, a member having one end pivotally connected with the remaining end of said link, and means to operate said member to operate said bolts through the intervention of said link and lever, said means including a pivoted dog carried by said member.

JOSEPH C. ALLMAN.
